UNITED STATES PATENT OFFICE.

CHARLES W. BECK, OF DETROIT, MICHIGAN, ASSIGNOR TO BECK-FROST CORPORATION, OF DETROIT, MICHIGAN, A CORPORATION OF MICHIGAN.

OIL-CAN HOLDER.

Application filed February 17, 1919. Serial No. 277,391.

To all whom it may concern:

Be it known that I, CHARLES W. BECK, a citizen of the United States of America, residing at Detroit, in the county of Wayne 5 and State of Michigan, have invented certain new and useful Improvements in Oil-Can Holders, of which the following is a specification, reference being had therein to the accompanying drawings.

10 My invention relates to holders for oil cans or the like and resides in the provision of a simple construction of a holder that may be easily and cheaply manufactured; in the provision of a holder that will readily adjust itself to the can and which is so constructed as to firmly hold the bearings and the holder in contact, so as to prevent rattling. Further, in the provision of a simple construction of holder by which the can will 20 be retained against accidental displacement.

The invention consists in the peculiar construction, arrangement and combination of parts as hereinafter set forth and particularly pointed out in the claims.

25 In the drawings:

Figure 1 is a perspective view of the holder embodying the invention;

Figure 2 is a side elevation showing the oil can in engagement with the holder, and

30 Figure 3 is a bottom view of the holder; the normal position of the oil can engaging member being shown in full lines and one of its positions of angular adjustment in dash lines.

35 In these views, A designates an attaching section having apertures B therein for receiving securing screws or the like to mount said section upon a suitable support. The member A is integrally formed at one side 40 thereof with a forwardly projecting tongue C, upon which is carried a supporting section D in the form of a wide, flat plate resting at its rear end upon said tongue and pivotally secured thereto as indicated at E.

45 The rear edge of the plate D is slightly rounded as indicated at E' at the side adjacent the pivot E so as to afford the necessary clearance to permit swinging of said plate. F and G are lugs struck out from

50 the lower edge of the section A and from the plate D respectively, and H is a spring having its ends respectively connected to said lugs to hold the supporting plate D normally against the member A, but permitting

said supporting plate to be swung upon the pivot E as shown in Figure 3.

I is a retaining projection or lug struck out of the plate A and bowed forwardly out of the plane of said plate. At the forward end of the plate D is a retaining section 60 preferably comprising spaced upturned lugs M and N which are slightly bent toward the plate A, and said lugs, as well as the projection I, are so shaped and proportioned as to engage over the flared portion O at the base 65 of the can P, as shown in Figure 2. When the can is in engagement with the holder, it is arranged as shown in Figure 2. In this position the spring H acts to yieldably draw the lugs M and N towards the 70 lug I, since the plate D is pivoted adjacent one side thereof. Since the lower or free end of the lug I is somewhat rounded, it is merely necessary to lift the can upwardly 75 in removing the same from the holder and the projection I will effect a gradual rocking of the member D about its pivot E, thereby moving the lugs M and N away from said projection and allowing the can to be withdrawn. To engage the can its edge 80 is first engaged with the lugs M and N and then the can is moved downward into engagement with the lug I. Since the latter is rounded, it will cause a rocking of the member D upon its pivot until the edge of 85 the can has passed below the lug I. The springs H will then cause the lugs M, N and I to yieldably engage the can. As will be readily apparent, the spring H will take up any play between the lugs and the can, 90 thereby preventing rattling.

In the construction described, the oil can holder is not only provided with suitable retaining lugs for engaging the can, but also has resilient means for taking up any play 95 between the lugs and the periphery of the can, so as to prevent rattling.

This application is an improvement upon the oil can holder shown in applicant's Patent 1,297,435, issued March 18, 1919. 100

What I claim as my invention is:

1. In a holder for oil cans or the like, the combination with an attaching plate, of a supporting plate pivoted thereupon and extending substantially at a right angle therewith, a spring connecting said plates acting to move the supporting plate toward the attaching plate, a tongue struck-out of the at-

taching plate at the side thereof against a zontal plate for supporting an article, of a 30
which the supporting plate abuts, and a securing plate for the supporting plate ex-
projection upon the supporting plate co-
acting with said tongue to engage an article
5 resting upon the supporting plate.

2. In a device of the character described, the combination with an attaching plate, of a supporting plate pivoted thereupon and extending substantially at a right angle 10 therewith, a spring connecting said plates urging the supporting plate toward the attaching plate, a tongue struck-out of the attaching plate, and a projection upon the supporting plate for acting with said tongue 15 to engage an article upon the supporting plate.

3. In a device of the character described, the combination with an attaching plate, of a supporting plate mounted thereupon and 20 extending substantially at a right angle therewith, and movable to or from said sup-
porting plate, a spring urging the supporting plate toward the attaching plate, a tongue struck-out of the attaching plate, and a pro-
jection upon the supporting plate coacting 25 with said tongue to engage an article upon the supporting plate.

4. In a device of the character described, the combination with a substantially hori- 30

zontal plate for supporting an article, of a 30
securing plate for the supporting plate ex-
tending above the latter and forming sub-
stantially a right angle therewith, means
pivotally mounting the supporting plate
upon the securing plate, a spring urging the 35
supporting plate pivotally toward the sec-
uring plate, and an upstanding projection
upon the supporting plate remote from the
securing plate and co-acting directly with
said plate to retain the supported article. 40

5. In a device of the character described, the combination with a relatively transverse supporting plate and securing plate, means pivotally mounting the former upon the latter, the pivot being adjacent the securing plate and adjacent the lateral edge of the supporting plate, a corner of the supporting plate adjacent the pivot being cut away to avoid interference by the securing plate with 45
pivotal movement of the supporting plate, a spring urging the supporting plate toward the securing plate, and an upstanding projection upon the supporting plate co-acting with the securing plate to retain an article 50
upon the supporting plate. 55

In testimony whereof I affix my signature.

CHAS. W. BECK.
